(57) **CLAIM**

The ornamental design for a portable electric oven, as shown and described.

DESCRIPTION

FIG. 1 is a perspective view of a portable electric stove with the handle in an up position showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a bottom plan view thereof;

FIG. 7 is a left side elevational view thereof; and,

FIG. 8 is a perspective view thereof with the front and right side doors in an open position.

The electric cord shown in FIGS. 1 and 4 and the pans in FIG. 8 are shown for illustrative purposes only and form no part of the claimed design.
